DEVICE FOR HANDLING AND AIRING MATTRESSES OR LIKE BULKY ARTICLES

De Quincey Vining, Manchester, Ga.

Application September 28, 1935, Serial No. 42,717

2 Claims. (Cl. 211—28)

This invention relates to carrying devices and more particularly to a device adapted for use in the handling of bulky articles which are relatively hard for one person to handle.

5 An object of this invention is to provide a carrying means of this type which is designed particularly for the handling of mattresses or like bulky articles for the purpose of moving the mattresses or like articles for cleaning, airing or the like.

Another object of this invention is to provide a device of this kind which includes means, whereby the position of the article may be changed so as to permit passage of the article 15 mounted on the device through a conventional doorway.

A further object of this invention is to provide an article carrying means of this kind which is relatively light in weight and which 20 can be easily manufactured at relatively low cost.

A still further object of this invention is to provide a device of this kind which is so constructed that it may be readily placed in a relatively small space so that it will not be in the way when it is not in use.

The above and various other objects and advantages of this invention will in part be described in, and in part be understood from the 30 following detail description of the present preferred embodiment, the same being illustrated in the accompanying drawing wherein:

Figure 1 is a perspective view partly broken away and in section of a device constructed according to an embodiment of this invention.

Figure 2 is an end elevation partly broken away and in section of the device with the supporting frame in substantially vertical position.

Referring to the drawing wherein like numerals of reference designate corresponding parts throughout the several views, the numeral 40 10 designates generally a base structure constructed of a relatively long piece of material, such as wood or the like which is provided 45 with a pair of transversely disposed bars 11 provided with casters or rollers 13. These bars 11 may be spaced apart the desired distance along the length of the base member 10, so that the device will not tilt either longitudinally or transversely.

The base 10 is provided with a pair of upstanding supports or standards 12 and 14 which are secured preferably to the base 10 at opposite ends thereof and these standards or uprights 12 and 14 may be braced as by angle

braces 15 secured to the inside portions of the standards and to the top of the base 10. It will, of course, be understood that other bracing means besides the angle braces 15 may be used, if considered necessary, to hold the uprights or standards 12 and 14 against rocking movement relative to the base member 10.

An elongated shaft 16 extends between the uprights or standards 12 and 14 adjacent the upper portion thereof, being secured as by cotter pins 17 so that the shaft 16 will not move longitudinally of the base 10, but may have rocking movement relative to the standards 12 and 14. An article supporting frame generally designated as 18 is mounted on the shaft 16 and 15 comprises a pair of spaced apart longitudinally extending parallel frame bars 19 disposed one on each side of the shaft 16, a pair of end rails 20 and 21, each provided with bearing members 22 extend transversely of the shaft 16 and are secured to the ends of the longitudinal frame bars 19. The frame bars 19 are secured as by nails or screws or other fastening devices to the end bars 20 and 21 at a point preferably intermediate the opposite ends of these end bars. 25

A pair of intermediate or transversely extending bars 22 are secured to the longitudinal bars 19 and disposed in parallel relation to the end members 20 and 21. A middle bar 23 is secured to the frame members 19 and is provided with 30 a relatively shortened portion 24 which is hinged to the balance of the bar 23 as by a hinge 25. This hinged portion 24 provides a means whereby a person pulling a mattress or other bulky article upon the slats or bars 21, 22 or 23 35 may stand relatively close to the carriage and in between the inner or intermediate slats or bars 22.

Each transversely disposed frame bar or slat is provided at opposite ends thereof, with a swingable locking member 26, which is constructed in the form of a staple or screw-eye which is adapted to engage in a selected elongated slot 27 provided in an end strap 28 secured to a locking bar 29. Each slat or transversely extending frame bar has a locking bar 29 associated therewith, and the locking bars 29 have straps 28 at each end thereof.

The supporting frame comprising the longitudinal bars 19, and the transverse slats 20, 21, 50 22, and 23 is held in a substantially horizontal position by means of a pivoted hook or locking member 30 carried by the standard 14 which is adapted to engage in a screw-eye 31 carried by the end slat 20. A diagonally disposed bar 32 55

extends through loops or screw-eyes 33 and 34 carried by the standard 12 and the base 10 respectively, and this bar 32 is adapted to hold the frame 18 in a substantially vertical position 5 when a mattress or like article is disposed thereon.

In the use and operation of this device the locking bars 29 are first removed from the transverse slats or bars carried by the frame 18 10 and then locked in a substantially horizontal position by the locking member 30. The side of the frame opposite from the hinged member 24 is then disposed adjacent the side or end of a bed and the hinged portion 24 swung in the 15 direction of the adjacent longitudinal bar 19 so that a person may readily stand between projecting ends of the inner transverse bars 22. The mattress or like article is then drawn upon the 20 slats of the frame 18 whereupon the locking members 29 are disposed on top of the mattress with the straps 28 engaging over the opposite sides or edges of the mattress. The screw-eyes or locking members 26 are then turned so that they may engage in a selected slot 21 of the 25 straps 28 in order to tightly clamp the mattress upon the frame 18. When the mattress or like article is clamped on to the frame 18 the locking member 30 is released so as to permit the swinging of the frame 18 to a vertical position. 30 In this position the frame 18 will bear against the bar 32. The device may then be rocked to the desired point whereupon the mattress may be left in a vertical position or may be swung to a horizontal position and cleaned upon the 35 frame if desired or left in the sun for airing.

This device is constructed of relatively few parts and the weight of the device by itself is relatively small so that one person can handle

a relatively bulky article which in itself is not very heavy but is of a flexible construction in addition to being relatively bulky.

It is, of course, understood that various changes and modifications may be made in the 5 details of construction and design of the above specifically described embodiment of this invention without departing from the spirit thereof, such changes and modifications being restricted only by the scope of the following claims. 10

I claim:—

1. A device as set forth comprising a base, uprights carried by the base, a relatively flat frame between the uprights, means for swingably securing the frame to the uprights, said frame including a plurality of parallel slats disposed in spaced relation to each other between the uprights, means for securing the slats together, at least one of said slats having a hinged section, a clamping bar for each slat, a pair of flexible 20 straps secured one to each end of each clamping bar and provided with a plurality of spaced apart slots and a locking member carried by each end of each slat and engageable in a selected slot of a strap to detachably hold the bars in 25 clamped position.

2. A device as set forth comprising a base, uprights carried by the base, and a frame swingably supported between the uprights, said frame comprising a pair of longitudinal frame bars disposed in parallel relation, a plurality of transverse bars secured to said longitudinal bars and projecting laterally thereof, a clamping bar for each transverse bar and adjustable means for securing each clamping bar in a position overlying 30 a transverse bar to clamp an article between said transverse bars and said clamping bars. 35

DE QUINCEY VINING.
